TRIPOD SUPPORT

Ray S. Lindenmeyer, Evanston, Ill.

Application October 1, 1956, Serial No. 43,153

Term of patent 14 years

(Cl. D15—8)

Fig. 1 is a perspective view of the tripod support embodying my new design;

Fig. 2 is a side elevational view of the tripod support of Fig. 1; and

Fig. 3 is a top plan view of the tripod support of Fig. 1. Characteristic features of my new design reside in the portions shown in solid lines in the drawing.

I claim:

The ornamental design for a tripod support, substantially as shown and described.
